United States Patent Office

Des. 185,508
Patented June 16, 1959

185,508

PLAYGROUND DEVICE

Edgar R. Overton, Oakland, Calif.

Application June 23, 1958, Serial No. 51,469

Term of patent 14 years

(Cl. D34—5)

Figure 1 is a side elevational view of the playground device embodying my new design.

Figure 2 is a front elevational view of the device shown in Figure 1.

I claim:

An ornamental design for a playground device, as shown.
